UNITED STATES PATENT OFFICE.

ROBERT FISHER, OF NEW YORK, N. Y.

DESIGN FOR A TIE-CLIP.

SPECIFICATION forming part of Design No. 32,811, dated June 12, 1900.

Application filed April 30, 1900. Serial No. 15,018. Term of patent 7 years.

To all whom it may concern:

Be it known that I, ROBERT FISHER, a citizen of the United States, residing at New York, in the county of New York and State of New York, have invented and produced a new and original Design for Tie-Clips for Use in the Construction of Walls, Ceilings, Partitions, &c., for Buildings, of which the following is a specification, reference being had to the accompanying drawings, forming part thereof.

Figure 1 is a view in perspective showing my new design of tie-clip. Fig. 2 is a side view, and Fig. 3 is a front view thereof.

As shown in the drawings, the leading or material feature of my design consists of the two parts A B, arranged at a right angle to

each other, as viewed in Fig. 2. The part A terminates in a point *a*, and the part B is cut away centrally to provide an opening *b* and *b*², an outwardly-extending shelf or projection, which is approximately semicircular, as viewed in Fig. 1.

Having described my invention, what I claim as new, and desire to secure by Letters Patent, is—

The design for a tie-clip, as herein shown and described.

In testimony whereof I affix my signature in the presence of two witnesses.

ROBERT FISHER.

Witnesses:

CHARLES A. RYDER,
ANNETTE HELWIG.
